(57) **CLAIM**

The ornamental design for a spear tip cover, as shown and described.

DESCRIPTION

FIG. 1 is a rear left perspective view of the spear tip cover of the present invention;

FIG. 2 is a front right perspective view thereof;

FIG. 3 is a top view thereof;

FIG. 4 is a bottom view thereof;

FIG. 5 is a right side view thereof;

FIG. 6 is a left side view thereof;

FIG. 7 is a rear view thereof;

FIG. 8 is a front view thereof;

FIG. 9 is an environmental view illustrating the spear tip cover in cooperation with a spear; and,

FIG. 10 is a partial environmental view taken along lines 10-10 of FIG. 9 illustrating the spear tip cover in cooperation with a spear.

The portions of the Figures illustrated in broken lines form no part of the claimed subject matter.
